UNITED STATES PATENT OFFICE

WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

SWITCH MECHANISM

Application filed May 27, 1929. Serial No. 366,345.

My invention relates to switch mechanism and particularly to switches for controlling current used in street cars and the like.

An object of my invention is to provide a switch that is capable of use in circuits carrying heavy current values and is relatively compact in construction in order that it may be used in installations where space limitations preclude the use of switches of large 10 dimensions.

A further object of my invention is to provide a switch, having the above-noted characteristics, wherein the parts thereof may principally be stamped from sheet metal and 15 assembled with a minimum of effort.

A further object of my invention is to provide a switch wherein the switch arm is part of a toggle assembly and wherein the contact thereof slides over the fixed contact during 20 opening movement thereof, thereby rendering the contacts self-cleaning.

A further object of my invention is to provide a switch that may readily be assembled between the pole pieces of a blowout 25 magnet of substantially standard construction.

A further object of my invention is to provide a switch wherein the switch mechanism is mounted between pole pieces of a 30 blowout magnet and wherein the fixed contact is mounted upon an insulating support of U-shape that is spaced from the pole pieces to constitute a support for the switch mechanism, and attached thereto adjacent to the 35 extremities of the support, whereby the creepage distance between the contact and the pole pieces of the magnet is substantially increased.

These and other objects that will be made 40 apparent throughout the further description of my invention are obtained by means of the switch apparatus hereinafter described and illustrated in the accompanying drawings, wherein,

45 Figure 1 is a longitudinal section through switch apparatus embodying features of my invention, taken on the line I—I of Fig. 2.

Fig. 2 is a plan view of the switch device shown in Fig. 1.

50 Fig. 3 is a longitudinal sectional view simi-

lar to that shown in Fig. 1 but with the switch parts shown in open position.

Referring to the drawings, the switch device comprises a metal supporting structure 4 of U-shape in cross section that serves as a base or support for the switch apparatus to be hereinafter described, and a blowout coil 5 and pole pieces 6, which are of the usual construction and which extend longitudinally of the support between the side walls 7 thereof, as indicated in Figs. 1 and 2. Insulating plates are disposed adjacent to the inner sides of the pole pieces to form an arc chute 9 in which the arc, incident to the opening of the switch contacts, is drawn and from which it is moved, under the influence of a magnetic field, between the pole pieces of the electromagnet coil 5.

The fixed contact of the switch device comprises a metal plate 11 that is mounted upon the bottom of an insulating support 12 of U-shape, the integral sides 13 of which are spaced from the side plates 7 by insulating washers 14, the side plates of the insulating support being attached to the side plates 7 of the main support by means of rivets 15. By reason of this construction, a maximum creepage distance is provided, within the space limitations of the device, between the contact plate 11 and the side plates 7 of the main support, which, as will be shown later, are conductively connected to the switch arm. The contact plate 11 is connected to one terminal 16 of the blowout coil.

The switch arm comprises a pair of toggle links 17 and 18, the former being provided, at its free end, with a contact member 19 that is disposed between a pair of plates constituting the free link 17, the contact member 19 being cylindrical in form and so mounted and frictionally clamped between the plates of the link 17 that it may be turned, when desired, to bring a different portion thereof into engagement with the contact plate 11. The link 18 comprises two spaced plates that are pivotally mounted upon a shaft 21 and positioned by means of spacing sleeves 22, as indicated in Fig. 2. The links 17 and 18 are connected by knee pivot bolts 23 or may be pivotally connected by rivets, as desired.

Arms 24 of the plates of the pivotal link 18 extend beyond the side plates 7 and their outer ends are connected by a bolt 26 and a sleeve 25 to constitute an operating handle 5 for the switch. Movement of the operating arms 24 is limited by stops 27 and 28 that are bent inwardly from the edges of the plate 7 of the support, and the stop 28 serves also as a stop for arresting opening movement of the free link 17.

10 A tension spring 29 is connected, at one end, to the pivot shaft 21 of the pivotal link 18 and, at its other end, to a pin 31 that is connected to the free end of the link 17, as indicated in Figs. 1 and 2. The spring 29 normally tends to fold or collapse the toggle links 17 and 18 and causes the angular position of the link 17 to be reversed with respect to the link 18 when the knee pivot 23 of the toggle is moved past a center line connecting the pivot shaft 21 and the shaft 31.

As shown in Fig. 1, the switch parts are in the closed position wherein the arms 24 are yieldingly pressed against the stop 27, 25 and the contact 19 is yieldingly engaging the fixed contact plate 11. When it is desired to open the switch, the operating arms 24 are turned counter-clockwise, thus moving the knee pivot 23 past the center line referred to 30 above. When this occurs, the spring 29 contracts and causes a reversal of the position of the free link 17 to the open position, wherein it will be seen that the opening movement of the link 17 is arrested by the stop 28, which 35 also serves to limit the movement of the operating handle. The spring 29 retains the parts in the open position shown in Fig. 3 until the operating handle has been returned to its original position, wherein the contact member 19 is in engagement with the fixed contact 11.

40 Referring to Fig. 1, it will be noted that, when the operating arms 24 are moved in a counter-clockwise direction, the links 17 and 18 are moved to a straightened position, thus causing sliding movement of the contact 19 from the full-line closed position to the line indicated in broken lines in Fig. 1, before the link 17 is actually moved to its circuit-opening position. This sliding or wiping action, 45 during each opening operation, tends to clean the contact, and it will be noted that the contact 19, at the moment of actual separation from the contact 11, is a considerable 50 distance from the original point of contact. Thus, any arcs that are drawn upon separation of the contacts do not burn the portion of the contact normally in engagement with the contact member 19 while the switch is in 55 closed position. Since the contact 19 may be rotated to bring a new surface into engagement with the contact plate 11 when the switch is in closed position, clean, smooth contact surfaces may be maintained in 60 engagement.

From the foregoing, it is apparent that a compact, rugged and effective switch is provided, capable of use in inductive circuits having relatively high current values, such as in railway service and where only one side 70 of the circuit is opened and that the switch is inexpensive to manufacture and may be disposed in places where space limitations are an important factor.

75 While I have illustrated but one embodiment of my invention, it will be apparent to those skilled in the art that various changes, modifications, substitutions, additions and omissions may be made in the apparatus illustrated, without departing from 80 the spirit and scope of my invention as set forth in the appended claims.

I claim as my invention:

1. A switch comprising a support having a pair of side members, a switch arm conductively connected to the support, a contact member between the side members adapted to be engaged by the side members and an insulating support of U-shape for supporting the contact member, the side plates of the insulating support being spaced from the side members and connected thereto adjacent the extremities of the plates to provide maximum creepage distance between the contact and the side members of the support.

90 2. A switch comprising a U-shaped support, a switch arm pivoted between the side members of said U-shaped support and conductively connected thereto, an insulating member of U-shape having a contact member in the bottom thereof, said insulating member being in contact with said U-shaped support only at points spaced from said contact member to provide maximum creepage distance between the contact and the support.

100 3. A switch comprising a U-shaped support, a pair of pivotally connected toggle links, one of which is pivoted between the side members of the U-shaped support and provided with an operating handle extending without the U-shaped support, the other of said toggle links carrying a contact member, an insulating support carrying a stationary contact and secured to the U-shaped support only at points at a distance from 105 said stationary contact.

110 4. A switch comprising a supporting member having parallel walls, a fixed contact and a movable contact, said fixed contact being mounted between said walls by an insulating member spaced from said walls and secured thereto only at a point at a distance from the fixed contact to provide maximum creepage distance between the contact and the support.

115 In testimony whereof, I have hereunto subscribed my name this 20th day of May, 1929.

120 WALTER H. SCHRAMM.
